ELI S. McCaulley, of Montour, Iowa, assignor of one-half to
Thomas U. Frantz, of Montour, Iowa.

BOW-FACING OAR.

SPECIFICATION forming part of Letters Patent No. 738,695, dated September 8, 1903.

Application filed November 28, 1902. Serial No. 138,160. (No model.)

To all whom it may concern:

Be it known that I, ELI S. McCaulley, a citizen of the United States, residing at Montour, in the county of Tama and State of Iowa, have 5 invented certain new and useful Improvements in Bow-Facing Oars, of which the following is a specification.

This invention relates to certain new and useful improvements in bow-facing oars by 10 which the oars are automatically feathered—that is to say, the blades are held in a vertical position during their effective stroke and held in a horizontal position on their return stroke, and, further to provide simple, durable, and 15 easily-adjusted means whereby the oars may be turned as required in feathering at the end of a stroke at any desirable point throughout the length of the stroke, so that the operator may take a stroke of any ordinary length and 20 have the oars feathered in the required manner at each end of the stroke.

My invention consists in certain details in the construction, arrangement, and combination of the various parts of the device whereby 25 the objects contemplated are attained, as hereinafter more fully set forth, pointed out in my claims, and illustrated in the accompanying drawings, in which—

Figure 1 shows a top or plan view of one of 30 the oars, the handle and blade portion being broken away and the covering-plate on top of the toothed segments removed. Fig. 2 shows a vertical central sectional view of the parts illustrated in Fig. 1. Fig. 3 shows a top or plan view of a portion of the device, illustrating the adjustable guide-plates. Fig. 4 shows an enlarged detail view illustrating the feathering-block. Fig. 5 shows a top or plan view of a portion of a row-boat with one of 35 my improved oars connected therewith as in practical use. Fig. 6 shows a detail edge view illustrating the base-plate, one of the adjustable guide-plates, and the feathering-block and showing by dotted lines the position of 40 the feathering-block when partially inserted; and Fig. 7 shows an edge view of same, illustrating the positions of the tripping-arms of the adjustable guide-plates and showing the feathering-block in position between them.

Referring to the accompanying drawings, I have used the reference-numeral 10 to indi-

cate a circular plate supported upon the edge of a boat 11 by the braces 12. On top of the plate 10 is a socket 13, having a set-screw 14.

The numeral 15 indicates a Y-shaped 55 bracket having its shank admitted into socket 13, where it may be clamped in position by set-screw 14. Between the sides of the Y-shaped bracket 15 is a base-plate 16, said base-plate being held in position so that it may tilt 60 in a vertical plane by means of the screws 17. Formed integral with plate 16 are two vertical journals 18, for purposes hereinafter made clear, and near one end of the base-plate is a circular groove 19, centering one of the journals 18 and arranged concentrically therewith. The ends of the base-plate 16 are semicircular in outline, and in the upper face thereof are the recesses 20, leading from the groove 19 outwardly. Slidingly mounted in this groove 65 70 75 80 85 90 95 100 19 are two adjustable guide-plates 21 and 22, each provided with a downwardly-inclined portion 23 and each having a integral arm projecting outwardly therefrom through the recess 20, one of these arms projecting straight outwardly and the other one, 25, inclined first downwardly and then outwardly, as clearly illustrated in Fig. 7, said arm 25 being materially longer than arm 24, and on each arm is a winged nut 26 to engage the outer face 80 of the block 16. The meeting end portions of the plates 21 and 22 are each reduced in width, so that they may lie parallel with each other and be capable of adjustment to and from each other while preserving a flat-topped 85 surface at any point throughout such adjustment, as clearly illustrated in Fig. 3. As will hereinafter appear, the depressions or downwardly-inclined portions 23 of these guides are for the purpose of permitting the feathering-block to turn at right angles, and by means of the construction just described these depressions 23 may be adjusted to and from each other and independently of each other, so that the feathering of the oars may take place at 90 any desired point throughout the stroke of the oars, and this is accomplished by loosening the winged nuts 26, then moving the arms 24 and 25 to the desired position, and then securing said arms in position by tightening the winged nuts.

Mounted upon one of the journals 18 is a

toothed disk 27, having an integral socket 28 at one end, in which a handle 29 is fitted. The numeral 30 indicates a mating disk the teeth of which are meshed with those of the 5 disk 27, and the disk 30 is mounted on the remaining journal 18.

Formed integral with the disk 30 is a socket 31, in which an oar-blade 32 is rotatably mounted, said blade being provided with a 10 rounded extension 33. Passed through the socket 31 toward the central portion of the disk 30 and fixed to the end of said part 33 is a swiveled block 34, having rollers 35 at its corners. This block 35 is mounted in a recess 15 36, formed in disk 30, and the feathering-block 34 is so arranged and proportioned as to rest upon the top of the guides 21 and 22.

Fixed to the part 33 are two pins 37 and 38, arranged at right angles to each other and each 20 projected through a slot in socket 31, and on top of the disks 27 and 30 is a covering-plate 39, resting on the tops of journals 18 and held in position by the screws 40.

In practical use it is obvious that the oars 25 complete may be readily carried and detachably connected with the plate 10 by passing the Y-shaped bracket through said socket 13 and clamped in position by means of said screw 14. When in this position, it is obvious 30 that the operator may face the bow of the boat and by manipulating the handle 29 in the manner in which ordinary oars are used he may face the bow of the boat and propel the boat in the same direction in which he is 35 facing, the motion imparted to the handle 29 being reversed as applied to the blade of the oar by the toothed disks 27 and 30. However, for the successful use of a pair of oars the blade should be reversed and firmly held in 40 a vertical position during the effective part of the stroke and also left and firmly held in a substantially horizontal position during the return stroke.

In describing the operation of the feathering device we will assume that the oar is in 45 position elevated above the water. At the start of its effective movement the oar is lowered into the water by means of the feathering-block 34, resting upon the flat-topped surface of the plates 21 and 22. Then as the blade 50 approaches the rearward limit of its effective stroke the pin 38 strikes against arm 24 and at the same time the forward corner of block 34 enters the depression 23, thus permitting the 55 block 34 to tilt, as illustrated by dotted lines in Fig. 6, and when the feathering-block 34 rests upon the bottom of the depression 23 the blade will be thrown to a horizontal position. During this time the blade is raised from the 60 water by depressing handle 29 and the block 34 rises out of the depression 23 and moves upon the top of the plates 21 and 22, thus firmly holding the blade in a horizontal position during such rearward movement. Then 65 the pin 37 strikes the arm 25, thus tilting block 34, as it enters the depression 23 in plate 22,

thus throwing the blade again to a vertical position, and when the oar is started again on its effective movement the said block will move out of the depression 23 to the flat tops 70 of the plates 21 and 22 to the position first described. The arms 24 and 25 are located in different horizontal planes and the pins 37 and 38 are of such length that only the pin 37 will strike arm 25, the pin 38 being short enough 75 to clear said arm and the arm 24 is shorter than arm 25, so that the pin 37 will not strike the arm 24 when passing it.

Having thus described my invention, what I claim, and desire to secure by Letters Patent of the United States therefor, is—

1. An improvement in bow-facing oars, comprising in combination a handle portion having at one end a concentrically-pivoted disk having a toothed rim, a blade portion 85 having a concentrically-pivoted disk provided with a toothed rim in mesh with the other rim, means for automatically turning the blade portion at each end of the stroke, means for firmly holding the blade portion in 90 position during both its effective and return movements, said means for turning the blade being adjustable whereby the length of the blade stroke may be changed and the blade turned at each end of the stroke. 95

2. An improvement in bow-facing oars, comprising in combination a base-plate capable of tilting in a vertical plane, an oar-handle portion having a toothed disk at one end concentrically pivoted to the base-plate, a 100 socket having a toothed disk at one end concentrically pivoted to the base-plate, said disks being meshed, a guide mounted in the base-plate and having a depression in its top surface, an arm connected with the guide and projecting radially therefrom, a clamping-nut on said arm, a blade portion rotatably mounted in the socket, a feathering-block on the blade portion normally resting upon said guide and a pin fixed to the blade portion to 110 engage the said arm, the parts being so arranged that when the pin strikes the arm the said feathering-block will be turned and enter the said depression, for the purposes stated. 115

3. An improvement in bow-facing oars, comprising in combination a base-plate capable of tilting in a vertical plane, an oar-handle portion having a toothed disk at one end concentrically pivoted to the base-plate, a 120 socket having a toothed disk at one end concentrically pivoted to the base-plate, said disks being meshed, two segmental guides having their ends projected past each other in the same horizontal plane and each having a depression in its top surface, a short straight 125 arm fixed to one of said guides, a long arm fixed to the other guide extended downwardly and then outwardly, means for clamping these arms in any position in which they may be placed, a socket formed on the last-mentioned 130 toothed disk having said blade passed through it and rotatable therein, a short and long pin

fixed to the blade and projected through the socket to engage respectively the short and long arms, and a feathering-block fixed to the blade and mounted in an opening in the disk, 5 said block having rollers at its corners designed to travel on the guides and capable of turning when they enter said depressions in

the guides, substantially as and for the purposes stated.
